UNITED STATES PATENT OFFICE.

ELMER E. GEESE, OF FRESNO, CALIFORNIA.

DEVICE FOR SPLITTING FIGS.

1,377,828.

Specification of Letters Patent. Patented May 10, 1921.

Application filed March 1, 1920. Serial No. 362,352.

To all whom it may concern:

Be it known that I, ELMER E. GEESE, a citizen of the United States, and resident of Fresno, in the county of Fresno and the 5 State of California, have invented a new and useful Improvement in Devices for Splitting Figs, of which the following is a specification.

My invention relates to a device for splitting figs. To those familiar with the art 10 of grading and packing figs it is well known that if a fig is soured, or has smut growing therein, such defects in that fruit can be more readily perceived if the fig is split 15 open and the inside of the fig exposed, and further, that in the packing of figs they make a better appearance when they are split open, spread and pressed flat. Heretofore in the fig packing industry the figs 20 have been cut by hand for this purpose, which at best is an expensive and unsanitary method inasmuch as each fig is individually handled just before depositing it in the carton or box. The object of my 25 invention is to produce a machine by which the figs can be laid in rows and drawn up to a knife and uniformly cut in a uniform position on the fig and the cut opened so that the inside of the fig can be inspected 30 without such figs being handled by the human hands after they are deposited in the hopper adapted to feed my machine.

I accomplish these and other objects 35 which will hereinafter appear by means of the device described in the specifications hereinafter set forth, and illustrated in the accompanying drawing in which Figure 1 is an isometric view of the machine from the left side. Fig. 2 is an independent view 40 of a block cam adapted to trip and disengage the latch pawl. Fig. 3 is an independent view of a cam adapted to close and lock the latch pawl for the clamping device. Fig. 4 is a top view of a fragment 45 of the carrier belt or draper. Fig. 5 is a side view of a latch pawl locking device. Fig. 6 is a view of a fragment of a clamping device, partly in section, showing the clamp open. Fig. 7 shows the same view as 50 Fig. 6 with the clamp closed. Fig. 8 is a view of fragments of two links used in forming and stiffening the draper. Fig. 9 is a sectional view of a portion of the machine through the line $\alpha-\alpha$ showing a plurality of knives or cutters, a spreading device, and knife cleaner. Fig. 10 is a top

sectional view of an adjustable shaft bearing. Fig. 11 shows a combination knife cleaner and fruit opener. Fig. 12 is a side view of the knife cleaner and fruit opener. 60 Fig. 13 is a similar view of the machine to Fig. 1 except from the opposite side. Fig. 14 is a side view of a miter gear drive showing shaft of varying lengths for driving portions of the machinery. Fig. 15 is a 65 cross sectional view of the shaft along the line $y-y$ on Fig. 14.

Fig. 16 shows the operative relation of a cam and a block hereinafter more definitely described. 70

In said drawings B is the main frame which is supported on legs B¹, B², B³ and B⁴. D and D¹ are duplicate wheels or drums adapted to rotate with axles 4 and 4^a in bearings 5 and 5^a, which are formed 75 in frame B, so that said axles 4 and 4^a are parallel with each other. E is an endless belt or draper, a detailed explanation of which will hereinafter appear, which is carried upon drums D and D¹, and which is 80 actuated by drum D. Draper E consists of a plurality of uniform size cross sections F which are hinged together so they form an endless belt. Each section F has a link 6, which link has a female portion of a hinge 85 6^b, and a male portion 6^a. These links are joined to a corresponding link on the sections next adjoining, so that the chain or belt formed thereby can have a movement 90 of the links relative to each other in line with the draper, but they form an approximately rigid connection as to cross sectional movements.

16 and 16^a are ordinary links of the same 95 length as link 6 pivoted at the ends to similar links and forming the outside edge of draper E. 8 is a rod slidingly fitted in a hole through the approximate centers of links 6, 16 and 16^a. 7 and 7^a are rigid ties 100 extending transversely across the draper and connecting links 16 and 16^a. One of said rods 7 and 7^a should be on each side of rod 8. 26 are a plurality of rods which extend from one side of the draper to the other, passing through the ends of links 6, 16 and 16^a forming hinge pivots between 105 such links and the next adjacent links.

9 and 9^a are a plurality of clamp jaws arranged in pairs. The upper portion of these jaws are beveled so that together they form 110 a V near the top, and just below the beveled portions the planes of the approaching sides

19 and 19^a are parallel. Jaw 9 is attached rigidly to rod 8 by means of a pin 12 shown in Figs. 6 and 7. Other suitable means may be substituted. Jaws 9^a are adapted to slide 5 on ties 7 and 7^a, and are attached rigidly to rod 8. Jaws 9 are slidably fitted in holes through rod 8 and are rigidly fastened to ties 7 and 7^a. In the device I have constructed there should be a plurality of jaws 10 9 and 9^a arranged in pairs on each section of the draper, set so the jaws will extend lengthwise with the draper, and they should be spaced so that when the rod 8 is moved laterally the clamp formed by jaws 9 and 9^a 15 will uniformly close and open.

H is a hopper adapted to deposit the figs placed therein on the top of the draper. Directly in front of the hopper there is rotatably journaled a rotary brush K which 20 extends transversely across the draper. The bristles of the brush lightly touch the top of the draper and the brush rotates in the opposite direction to the travel of the draper. The purpose of brush K is to distribute the 25 figs on the draper in the openings between the jaws 9 and 9^a, and in cases where there are deposited more figs than is necessary for the purposes set forth the brush will move them back on the draper allowing only 30 enough to pass sufficient to lay in a single row the depth of the thickness of one fig. 14 are a plurality of circular knives attached to shaft 13 adapted to rotate, are spaced on the shaft so they will pass in line with jaws 35 9 and 9^a and midway between them, the object being that as the figs lined on the draper between the jaws 9 and 9^a pass under the knives they are split at a predetermined depth. In order that the figs may be rigidly held as they pass under the knives I 40 have constructed a device for moving the jaws together, locking them and releasing them as follows:

Rod 8 has an extension 8^a to which a lever 45 20 is pivoted between the ends. 7^b is an extension of tie 7^a and is a fulcrum for lever 20. The end of lever 20 opposite the fulcrum is fitted with a roller 20^a. 15 is a cam attached to frame B in line with the travel 50 of roller 20^a and is adapted to press the roller toward the draper and necessarily move each jaw attached thereto toward the other jaw of the same pair of jaws, clamping any object which may be between them. 55 The cam 15 is placed in a position so that the jaws 9 and 9^a clamp on the line of travel between brush K and knives 14. For the purpose of holding the jaws rigidly in such clamped relation I have formed a notch 10^a 60 in rod 8, and on the top of link 6 I have placed a latch 10 which operates through a hole 10^b, in link 6, and when rod 8 is moved so that the notch 10^a is directly under hole 10^b, latch 10 will drop into it and lock rod 8 65 in relation to link 6, and with the clamp

jaws 9 and 9^a adjacent to each other. On the top of link 6 I have placed a fulcrum 17, and have provided a lever 18. Lever 18 is pivoted at one end to latch 10, at the approximate center to fulcrum 17, and I have 70 provided a spring 17^a which normally holds the lever 18 in a position so that the latch 10 is pressing downward, thus being normally held in notch 10^a when placed therein. 18^a is a cam roller on the end of lever 75 18 opposite the end where latch 10 is pivoted. 22 is a cam guide in line with the travel of cam roller 18^a, and so adjusted that cam roller 18^a is depressed as it passes along guide 22, and by means of a spring 23 between link 16 and lever 20, rod 8 is moved so that the jaws 9 and 9^a open or separate. It is noted that in my arrangement the cam 80 guide is placed at a point of travel on cam rod so that it will not open until it has passed the knives.

For the purpose of adjusting the height of the knives 14 from the figs I have journaled shaft 13 in bearings 13^a and 13^b which are carried on the ends of rods 28^a and 28^b, 90 these rods being attached at the top to a cross tie 28, having a screw threaded hole 24^a therethrough. 31 is a cross bar having depending posts 31^a and 31^b spaced apart the same distance as rods 28^a and 28^b are apart. 95 In posts 31^a and 31^b I have formed slide-ways 25^a and 25^b to receive the bearing boxes 13^a and 13^b, these slides being arranged so that said bearing boxes have a vertical adjustment. Posts 31^a and 31^b terminate at 100 the end with rollers 34^a and 34^b. The frame composed of cross pieces 31 and posts 31^a and 31^b is fitted in vertical grooves 33^a and 33^b in the frame B directly above the draper. The width of the draper is predetermined so 105 that the links 16 and 16^a form a track for rollers 34^a and 34^b, and the weight of the knives and mechanism described will keep the knives at a fixed distance from the draper moving it up and down synchronously with similar movements of the draper. A further adjustment of the distance the knives are from the draper is made by means of a screw 24, operable in threaded hole 24^a in cross tie 28. 24^b is a socket in 110 cross piece 31 directly in line with screw 24, arranged to hold the end of the screw in a fixed relation to cross piece 31, so that by moving screw 24 downward shaft 13 will be lowered, and by moving the screw upward 115 the knives will be raised. Similar mechanism is used for adjusting and raising and lowering brush K on shaft 13.

30 is a rod attached to frame B set parallel with shaft 13 and directly to the rear 120 of cutters 14. To rod 30 I have attached a plurality of spreaders 51 and 51^a which operate in pairs. They are arranged so that one of said spreaders is on each side of each of the knives at its lower portion. The 125 130

purposes of the spreaders are twofold, one being to keep the knives clean by scraping them, for which purpose the spreader should bear against the face of the knives, and the 5 second object being to spread the figs apart. This latter object is accomplished by adjusting the spreaders so that the outline of each pair is a V with the apex at the cutting portion of the knife so they engage the figs in 10 the opening as they pass from the knives 14. After the figs are thus spread apart they can be readily examined and assorted.

M is a cylindrical brush, having an axis M¹ set parallel with shaft 4. This brush is 15 adjusted so that it will readily clean draper E and is preferably on the under side of the machine. The links forming the draper are approximately eight inches long, and the periphery of the drums D and D¹ are provided with projections 32 which are adapted 20 to engage the pivot rods 26 in the draper, thus giving the draper a positive movement with said drums. This form of draper and drums will give the top surface of the 25 draper a slight up and down movement as the draper moves with the rotation of the drums. As the knives 14 and brush K should maintain a constant fixed relation with the draper surface passing directly 30 under them, I have compensated for this variation in the draper by the mechanism hereinbefore described.

34 is a pulley attached to drum D¹, 34^a is the main belt operating pulley 34. By 35 means of draper E drum D is rotated. 35 is a pulley attached to drum D. 36 is a pulley on brush M. 36^a is a belt connecting pulley 36 with pulley 35. Pulley 35 has a beveled gear 37 attached thereto adapted to 40 drive a pinion 39. 40 and 41 are telescoping, sliding interlocking shafts connecting pinions 39 and 39^a. 41^a is a slot in shaft 41, and 40^a is a pin extending through shaft 40 and in slot 41^a, the object being to permit 45 shaft 40 to slide within shaft 41 and at all times to be rigid as to torsion movements. 43 is a pulley on shaft 13' carrying brush K and 43^a is a belt extending from pulley 38 to pulley 43. It will be observed that drum 50 D¹ is driven by the main belt, 34^a which drives draper E and drum D. Drum D drives brush M, and brush K and the pulley on the shaft carrying brush K drives knives 14. The object in connecting pinions 39 and 55 39^a with a sliding shaft is to keep pinions 39 and 39^a enmeshed with beveled gears 37 and 38 at all times even though the distance between beveled gears 37 and 38 varies. To do this more effectively shafts 13 and 13^a

60 rotate in bearings 44 and 44^a, and shafts 40 and 41 rotate in bearings 45 and 45^a. Bearings 44 and 45 are connected rigidly by a tie 46, and bearings 44^a and 45^a are connected with a tie 46^a. S is a shield or housing. 65

I claim as new and ask for Letters Patent:

1. In a device of the character described the combination of a draper constructed with a plurality of cross sections, each having a plurality of clamps constructed with 70 the jaws in line with the jaws on the next adjacent section, means for closing all the clamps on each cross section independently of the clamps on the other sections and keeping them closed while the draper is passing 75 a predetermined space in its line of travel, a hopper having an opening directly above the draper on a space where the clamps are open, a rotary brush extending across the draper on the upper surface thereof between the 80 hopper and the spaced portion of the line of travel where the clamps are closed, said brush being adapted to remove loose articles extending above the jaws of the clamps, a plurality of knives adapted to pass at a fixed 85 distance from the draper and aligned with the center line of the clamps, substantially as described.

2. In a device for holding and cutting figs, the combination of a draper adapted to 90 move laterally, a plurality of independent clamps on the outside surface of the draper, consisting of duplicate jaws, one jaw of such clamp being stationary relative to the draper and the other being attached to a rod slidably disposed transversely across the draper, 95 means for normally holding the clamps open, means for closing said clamps and holding them closed while the clamps on the draper are passing a fixed space in the line of travel 100 of the draper, and a plurality of knives held directly over the draper in said fixed space in line with the center line of the clamps and at a fixed space above them, substantially as described.

3. In a device for splitting and opening figs the combination of an endless draper composed of a plurality of similar cross sections, each of the cross sections containing a plurality of clamps the jaws of which extend 110 upward and the uppermost opening between them forming a V, automatic means for moving the jaws of each clamp closer together at a predetermined point of travel and thereafter automatically opening them, rotary 115 knives disposed so the plane of the knives register with the line between the jaws of the clamps, fruit spreaders consisting of blades, one of which is on each side of each rotary knife, one end of each blade being disposed to drag on the face of the knife adjacent to its lowest point of travel, and to 120 spread apart as it recedes from said knife, substantially as described.

4. In a device of the character described 125 the combination of a draper constructed with a plurality of similar cross sections each cross section containing a plurality of pairs of clamp jaws which are normally open and are adapted to close and remain closed while 130

the draper is passing a predetermined space in its line of travel, means for placing figs in single rows between such jaws while the jaws are apart, a plurality of knives arranged so that the edge of a blade of a knife will come in contact with each row of figs as they pass the knives, and wedge means disposed to enter and part the cut portions of the figs as the draper carries them beyond the knives, substantially as described.

5. In a device of the character described, the combination of a draper having a plural-

ity of sections hinged together, each section having a plurality of clamping devices consisting of jaws adapted to open by spring means and to close by a cam operated at fixed points on the line of travel of the belt, rotary knives adapted to travel between the jaws of said clamps as the draper passes beneath the knives, substantially as described.

ELMER E. GEESE.
